(57) **CLAIM**

The ornamental design for a replacement stamp pad, as shown and described.

DESCRIPTION

FIG. 1 is a front perspective view of the replacement stamp pad according to my invention with a lid in a partially uplifted position;

FIG. 2 is a front elevation of the replacement stamp pad of FIG. 1;

FIG. 3 is a side elevation of the replacement stamp pad of FIG. 2;

FIG. 4 is a planar top view of the replacement stamp pad of FIG. 2;

FIG. 5 is a front perspective view of an alternate embodiment of the stamp pad of my invention;

FIG. 6 is a front elevation of the replacement stamp pad of FIG. 5;

FIG. 7 is a side elevation of the replacement stamp pad of FIG. 5; and,

FIG. 8 is a planar top view of the replacement stamp pad of FIG. 5.
